SPINNING FRAME

Walter S. Eastman, Glendale, R. I., assignor to
Stillwater Worsted Mills, a corporation of
Rhode Island

Application June 19, 1940, Serial No. 341,323

20 Claims. (Cl. 19—130)

My invention relates to spinning frames. It has among its objects to provide an improved pressure mechanism of the type adapted to cooperate with the upper front roll of such a frame in divorcing the twisting of the yarn from the drafting function of the front rolls. A further object of my invention is to provide such improved pressure mechanism whereby it is made possible to improve prior devices of this type by eliminating the pressure roll heretofore used and the waste incident to lapping around such rolls, as well as the lubrication and other problems incident to such rolls. Other objects are to provide an improved pressure means adapted to cooperate in an improved manner with the top front drafting roll, and such an improved pressure means which is easier to control and adjust than such a pressure roll, and which reduces yarn breakage while enabling production to be increased. Still further objects of my invention are to provide an improved pressure means providing an enlarged concave pressure surface pressing the yarn against the top front roll in such manner as to provide more effective control and protection for the fibres in the interval between drafting and twisting, and also to provide such an improved construction having improved yarn supporting means whereby the fibres are more effectively kept in their desired relative positions as they pass from the nip of the front rolls to and through the improved pressure means cooperating with the top front roll. Other objects of my invention include the provision of an improved attachment adapted to cooperate in an improved manner with the top front roll of a standard spinning frame while enabling the above advantages to be obtained, and such an improved attachment adapted to be applied to such a frame at small expense. These and other objects of my improved construction will, however, hereinafter more fully appear.

In the accompanying drawing, I have shown for purposes of illustration one embodiment which my invention may assume in practice.

In the drawing:

Figure 1 is an end elevation of a spinning frame equipped with my improvement;

Fig. 2 is a partial front elevation of such a spinning frame;

Fig. 3 is a sectional view on line 3—3 of Figure 1;

Fig. 4 is an enlarged end elevation of my improved pressure plate;

Fig. 5 is a detail perspective view of the front

end of the pressure mechanism with the pressure plate carried thereon, and

Fig. 6 is a bottom plan view of the pressure plate.

- 5 In this illustrative construction, I have shown a spinning frame of standard construction and including a usual carriage stand 1 carrying usual drafting mechanism including front lower fluted rolls 2 and cooperating cork covered or other 10 suitable top rolls 3, as well as usual closed pigtail guides 4 disposed above the caps 5 of usual shirled bobbins 6; my improvements herein relating to improved pressure means, hereinafter described, and also adapted to cooperate in an 15 improved manner with the top front rolls 3 and carried on a usual lateral front extension on a usual swinging pressure frame 7 biased to operative position and pivoted in a usual manner on the front saddle bar of the stand 1.
- 20 These improved pressure means herein include improved pressure plates, generally indicated at 8, and each adapted to cooperate with one of the top front rolls 3, while each is carried by its own individual pressure frame 7 and pressed 25 thereby against the under side of its cooperating roll 3. Herein, each of these plates 8 is of substantially the length of the roll 3 and has a curved upper yarn pressing surface 9 of substantial width and substantially conforming to 30 and receiving a substantial part of the bottom portion of the periphery of the roll 3. Preferably the member 8 is formed of metal, and this surface 9 is a polished surface. Herein also it will be observed that a rounded edge 10 is provided on the rear edge of the plate 8, and that an enlarged and rounded edge portion 11 is provided along the opposite or front edge of the plate for supporting the yarn after it is freed from pressure and before it passes downward 35 over the rounded surface of the portion 11 to the pigtail 4, this edge portion 11 preferably also having its upper surface polished similarly to the surface 9. While other constructions may be utilized, I herein form the plate 8 and this edge 40 portion 11 of separate members integrally united, the plate herein being a thin steel plate, as, for example, a $\frac{1}{2}$ " plate, and bent to fit the top front roll, and the front edge portion 11 herein being in the form of a short length of round solid 45 steel rod suitably welded along one side thereof to the plate 8, as at 12. In a preferred construction, the under adjacent edge of the plate is also bevelled or cut away to provide a smooth junction between the plate and the adjacent 50 surface of the rod, while the latter surface pro-

vides a smooth, rounded downwardly directed continuation of the surface 9 leading directly toward the center of the pigtail 4. Further, on the under side of the plate 8 I herein suitably form or attach a universal or ball joint receiving socket member 13, centrally located both longitudinally and transversely relative to the plate 8. Herein, this socket member 13 receives a ball 14 on an upstanding portion 15 at the extremity of a transverse portion 16 on the front end of the swinging, herein weighted, pressure frame 7; this ball 14 herein being welded to the upper end of the portion 15.

In the operation of my improved construction, the plate 8 provides a pressure surface of substantial area in contact with and conforming to the curved under surface of the cork covered roll 3, as compared with a pressure roll wherein only a line contact between the latter and the top roll is obtainable. Further, it will be observed that the plate provides, in effect, an elongated carrier or conveyor supporting and pressing against the roll 3 a substantial part of the length of the section of thread, indicated at 17, which extends between the nip of the front drafting rolls 2 and 3 and the front edge 11 of the plate 8 where it will be observed that twisting begins in this construction. Thus, it will be observed that this plate, with its substantially greater pressure surface area as compared with a pressure roll, acts to keep the fibres in their relative positions at a new time, i.e. when, there being no twist acting to keep the fibres together, they would with a pressure roll only be maintained in thread form due to their affinity for each other. Thus, in my improved construction, the fibres are more effectively controlled and protected by my improved plate which very effectively acts to keep the fibres in their desired relative positions in the thread until twisting which herein begins at the front edge 11 of the plate, in a generally similar manner to other pressure devices of this type, i.e. while the fibres are free from pressure and are supported on a rounded yarn supporting portion on the pressure means.

As a result of my improved construction, since should the thread or yarn be broken, it can not wrap around the plate 8, the waste and trouble incident to lapping on the small pressure rolls previously provided, is also eliminated. Instead, the yarn tends to wrap around the roll 3 which, being of greater circumference, can accumulate a greater quantity of roving without causing trouble than it is possible to wind on a small pressure roll, while the accumulated roving is also more easily removable from the larger roll 3. Further, yarn breakage is materially reduced due to the increased protection for the yarn as it passes through the stage between the completion of the draft and the beginning of twisting, in such manner as to enable production to be increased. Attention is also directed to the fact that the correct location of the plate relative to the roll 3 is insured by the curvature of the plate and the ball and socket connection which cooperate to enable the plate to be retained in contact with the roll over the full area of the plate. At the same time, due to the ball and socket connection, it will be evident that while the plate will be pressed upward against the under side of the roll 3 by the pressure mechanism, this connection will enable the plate to conform to the roll 3 as necessary. Attention is also directed to the simplicity of the improved plate structure as com-

pared with a pressure roll, and to the advantages of the plate as regards freedom from trouble in operation, longer life, and elimination of need for lubrication. These and other advantages of my improved construction will, however, be clearly apparent to those skilled in the art.

While I have herein specifically described one embodiment which my invention may assume in practice, it will be understood that this form has been shown for purposes of illustration, and that the invention may be modified and embodied in other forms without departing from its spirit or the scope of the appended claims.

What I claim as new and desire to secure by Letters Patent is:

1. In a spinning frame, cooperating front drafting rolls, and means including an elongated yarn supporting carrier extending lengthwise along the yarn beneath the upper roll for maintaining the yarn under pressure and laterally spacing the beginning of twisting from the pressed portion of the yarn.

2. In a spinning frame, cooperating front drafting rolls, and means including an elongated yarn supporting carrier extending lengthwise along the yarn for enclosing and pressing against the upper front roll, the yarn passing laterally from the nip of said rolls.

3. In a spinning frame, cooperating front drafting rolls, and mechanism for divorcing the twisting of the yarn from the drafting function of said rolls including pressure means acting on a substantial length of the yarn and maintaining the latter under pressure in front of the nip of said rolls.

4. In a spinning frame, cooperating front drafting rolls, and mechanism for divorcing the twisting of the yarn from the drafting function of said rolls including pressure means acting on a substantial length of the yarn and maintaining the latter under pressure against a portion of the periphery of the top front roll.

5. In a spinning frame, cooperating front drafting rolls, and mechanism for divorcing the twisting function from the drafting function thereof including a pressure plate conforming to a portion of the periphery of the top front roll and pressing the yarn against the latter.

6. In a spinning frame, cooperating front drafting rolls, and mechanism for divorcing the twisting function from the drafting function thereof including a pressure plate pressing the yarn against the top front roll over a yarn supporting area of substantial width and length to maintain the fibres in their relative positions.

7. In a spinning frame, cooperating front drafting rolls, and mechanism for divorcing the twisting function from the drafting function thereof including a concave pressure plate pressing the yarn against the top front roll and having a yarn supporting front edge sloping away from said roll.

8. In a spinning frame, cooperating front drafting rolls, and mechanism for divorcing the twisting of the yarn from the drafting function of said rolls including a concave pressure means pressing the yarn against the bottom of the top front roll and having an enlarged rounded and downwardly directed yarn supporting edge portion in front of the concave portion thereof laterally spacing the beginning of twisting from the latter.

9. In a spinning frame, cooperating front drafting rolls, and mechanism for divorcing the twisting function from the drafting function

thereof including a concave pressure plate pressing the yarn against the periphery of the top front roll and having downwardly rounded front and rear edges.

10. In a spinning frame, cooperating front drafting rolls, and mechanism for divorcing the twisting function from the drafting function thereof including a concave pressure plate pressing the yarn against the top front roll and a pressure frame maintaining said plate in operative position.

11. In a spinning frame, cooperating front drafting rolls, and mechanism for divercing the twisting of the yarn from the drafting function of said rolls including means for pressing the yarn against the periphery of the top front roll and directing broken yarn toward the latter for lapping thereon.

12. In a spinning frame, cooperating front drafting rolls, and mechanism for divorcing the twisting function from the drafting function thereof including a concave pressure plate pressing the yarn against the top front roll, a pressure frame maintaining said plate in operative position, and adjustable connecting means between said plate and frame for enabling relative movement between the latter.

13. In a spinning frame, cooperating front drafting rolls, and mechanism for divorcing the twisting function from the drafting function thereof including a pressure plate pressing the yarn against the top front roll and a pressure frame maintaining said plate in operative position and having a ball and socket connection between said plate and frame centrally located relative to the latter.

14. In a spinning frame, cooperating front drafting rolls, and mechanism for divorcing the twisting of the yarn from the drafting function of said rolls including a pressure frame biased to operative position and having an upstanding extension underlying the top front roll, yarn supporting means pressing the yarn against said

top front roll, and a universal joint between said pressure means and said extension.

15. In an attachment for spinning frames having cooperating front drafting rolls, a pressure frame, and a pressure plate carried thereby and having a contact surface of substantial area adapted to be pressed by said pressure frame against the top front roll.

16. In an attachment for spinning frames having cooperating front drafting rolls, a swinging pressure frame, and a pressure plate carried thereby and having a concave contact surface of substantial area adapted to be pressed by said pressure frame against the top front roll.

17. In an attachment for spinning frames having cooperating front drafting rolls, a swinging pressure frame, and a pressure plate carried thereby and having a contact surface of substantial area adapted to be pressed by said pressure frame against the top front roll, said pressure plate being concave and having a swivel connection to said frame enabling said plate to conform to the roll.

18. In an attachment for spinning frames having cooperating front drafting rolls, a swinging pressure frame, a pressure plate having a concave contact surface of substantial area adapted to be pressed by said pressure frame against the top front roll, and a ball and socket connection between said plate and said frame.

19. In an attachment for spinning frames having cooperating front drafting rolls, a pressure plate having a concave pressure face, an enlargement forming the front edge of said plate, and a rounded yarn supporting surface on said enlargement.

20. In an attachment for spinning frames having cooperating front drafting rolls, a pressure plate having a concave pressure face and an enlarged rounded front edge and a rounded rear edge oppositely directed with respect to said front edge.

WALTER S. EASTMAN.
